COMBINED TOILET TISSUE HOLDER AND DISPENSER

Morris N. Knutsen, Olympia, Wash.

Application October 20, 1955, Serial No. 38,478

Term of patent 14 years

(Cl. D4—3)

FIG. 1

FIG. 2

FIG. 3

FIG. 4

Fig. 1 is a front perspective view of a combined toilet tissue holder and dispenser showing my new design;

Fig. 2 is a top plan view of Fig. 1;

Fig. 3 is a bottom plan view of Fig. 1; and

Fig. 4 is a side elevational view of Fig. 1 looking directly at the most remote side thereof.

The toilet tissue roll being shown by means of broken lines is only disclosed for purposes of illustration.

I claim:

The ornamental design for a combined toilet tissue holder and dispenser, substantially as shown and described.
